Primary Examiner — Messina L Smith*Assistant Examiner* — Kwabena A. Ankobiah(74) *Attorney, Agent, or Firm* — MUNCY, GEISSLER, OLDS & LOWE, P.C.(57) **CLAIM**

The ornamental design for a wearable device body as shown and described.

DESCRIPTION

FIG. 1 is a perspective view of a wearable device body showing the claimed design;

FIG. 2 is front elevational view thereof;

FIG. 3 is a rear elevational view thereof;

FIG. 4 is a right side elevational view thereof; a left side elevational view being symmetric to the left side elevational view;

FIG. 5 is a top plan view thereof; a bottom plan view being symmetric to the top plan view;

FIG. 6 is another perspective view thereof; and,

FIG. 7 is a perspective view showing the wearable device body being used with a strap.

The broken lines in the drawings depict portions of the wearable device body that form no part of the claimed design. The other broken lines showing a strap in FIG. 7 represent environmental subject matter only and form no part of the claimed design.
